UNITED STATES PATENT OFFICE.

RICHARD L. MARWEDE, OF NEW YORK, N. Y., ASSIGNOR TO HAMPTON GLAZED PAPER & CARD COMPANY, OF HOLYOKE, MASSACHUSETTS, A CORPORATION OF MASSACHUSETTS.

DESIGN FOR COVER PAPER.

Application filed July 31, 1925. Serial No. 14,283. Term of patent 14 years.

To all whom it may concern:

Be it known that I, RICHARD L. MARWEDE, a citizen of the United States, residing at New York, in the county of New York and State of New York, have invented a new, original, and ornamental Design for Cover Paper, of which the following is a specification, reference being had to the accompanying drawing, forming a part thereof.

The figure is a plan view of a piece of cover paper embodying my new and ornamental design.

I claim the ornamental design for cover paper as shown.
